CARL A. ALEXANDER AND ERIC W. YOUNG, OF TACOMA, WASHINGTON.

WAX-POT.

1,360,255.

Specification of Letters Patent. Patented Nov. 30, 1920.

Application filed April 8, 1920. Serial No. 372,314.

To all whom it may concern:

Be it known that we, CARL A. ALEXANDER and ERIC W. YOUNG, citizens of the United States, and residents of the city of Tacoma, county of Pierce, and State of Washington, have invented certain new and useful Improvements in Wax-Pots, of which the following is a specification.

This invention relates to improvements in wax pots, and more particularly to wax pots of that character adapted for use in connection with shoe sewing machines, or machines of like character, wherein liquid wax may be contained and through which the threads used in sewing may be drawn to apply the wax thereto.

It is the principal object of the invention to improve on pots as here before used, by providing for the waxing of several threads instead of the usual single thread, and in connection with the wax pot to provide an improved tensioning plate which may be adjusted to place a desired tension on the threads drawn through the wax and a supplemental spring-like arm for taking up slack in the thread between the pot and needle while stitching is being done.

In accomplishing these and other objects of the invention, we have provided the improved details of structure, the preferred forms of which are illustrated in the accompanying drawings, wherein—

Figure 1 is a perspective view of a wax pot constructed according to the present invention and equipped with a tensioning plate and spring arm.

Fig. 2 is a longitudinal sectional view of the same.

Fig. 3 is a transverse sectional view, illustrating the means for attaching the pot to a machine.

Fig. 4 is a plan view of the pot and tensioning plate.

Fig. 5 is a detail section view of the tensioning plate and bridge between which the threads are drawn.

In the most common type of wax pot, provision has only been made for two threads at a time, one of which extends to a needle and the other to a bobbin and in such pots when it is desired to use a smaller or larger thread it is necessary to unthread from the pot and then re-thread with the size desired.

In the present device, we have sought to facilitate the work of sewing by providing a pot wherethrough a plurality of threads

of different sizes may be kept threaded at all times, and the threads desired may be selected and used, and when not in use need not be unthreaded to make room for the one that is being used.

It is also intended to provide a single tensioning plate that will take care of all the different threads without unthreading.

In the drawings, 1 designates a wax pot embodying the present invention, and in its preferred construction, comprising an open-top receptacle wherein liquid wax may be contained, having parallel front and back walls 2 and 3, respectively, downwardly converging opposite side walls 4, and a bottom wall 5.

At the base of the pot are downwardly and laterally directed bosses, 7 and 8, each of which is provided with bores 9, opening into the base of the pot and to the outer ends of the bosses, and each bore is equipped with a plug 10. The plugs have squared wrench heads 11, whereby they may be threaded into or from the bores and have holes, or channels 12, therethrough, through which the threads are drawn.

The pot is preferably attached to the machine with which it is used by means of screw bolts, 15 and 16, which are extended through the upper and lower ends of the back wall 2.

Extending laterally at one side of the pot, at its upper end, is a flange 18, and mounted across the same close to the pot wall, is a bridge member consisting of a spring wire 19, having downturned end portions 20 which fit within grooves 21 cut in opposite edges of the flange, to hold the bridge in place. Also mounted on the flange is a tensioning plate 22, of suitable spring metal, having a downturned flange 23 at its outer end and a downwardly pressed transverse rib 24 spaced from the end which is adapted to seat upon the bridge wire and to space the plate slightly from the flange, and has an upwardly inclined portion 22' which serves as a releasing lever for the tensioning plate. A bolt 25 extends downwardly through the plate and flange and at its lower end has a thumb nut 26 threaded thereon, which may be tightened or loosened to regulate the pressure of the plate against the bridge.

The plate is also provided between the end flange 23 and rib 24 with a series of openings 28, here shown to be four in num-

ber, through which the threads used in stitching may be drawn, and also has two openings 50 through which posts 51 on the pot flange 18 extend to prevent lateral displacement of the plate.

5 A leaf spring 29 is also secured to the base of the pot by means of the screw 16 which has an eye 30 at its lower end through which the needle thread used in sewing is drawn 10 after it leaves the pot; the spring serving to take up the slack in the thread between the pot and needle.

Assuming that the pot is so constructed, and the tensioning plate and take up spring 15 are mounted as described, in using the device, threads indicated at 40, are drawn through the several openings 28 and are passed between the bridge wire 19 and rib 24 of the plate 22, then downwardly through 20 the openings 12 of the plugs 10. The thread selected to extend to the needle is then drawn through the eye of the spring arm 29 and the other thread is extended to the bobbin.

25 It is apparent that in this construction, by adjustment of the nut 26 a desired tension may be maintained on the several threads before they are drawn through the wax and that the spring arm 29 will act to 30 take up slack in the thread being used.

It will be seen that such a construction provides for the using of threads of different sizes without re-threading through the pot and much time otherwise lost in re-threading is eliminated.

35 What we claim as new, is:

1. In combination, a wax pot of the character described having a body portion and a laterally directed flange at its upper edge 40 and having a plurality of base openings, plugs threaded into said openings having longitudinal channels therethrough through which threads drawn through the pot may be extended, and a tensioning plate fixed to 45 said body flange to maintain tension on the threads.

2. In combination, a wax pot having a plurality of base openings and having a

laterally extending flange at an upper edge, 50 plugs, having longitudinal channels therein, threaded into the said base openings, through which threads drawn through the pot may be extended, a transverse bridge secured on the body flange across which threads drawn through the pot are passed 55 and a tension plate secured to the flange and yieldingly urged against said bridge and threads.

3. In combination, a wax pot having a plurality of base openings and having a 60 laterally directed flange at its upper edge, a transverse bridge secured on said flange adjacent the edge of the pot, a spring plate having a downpressed, transverse rib adapted to seat upon the transverse bridge and 65 having a downturned end engageable with the flange to space the plate from the latter, a bolt extending through the plate between the downturned end and rib, and through the pot flange, adjustable to tension the rib 70 of the plate toward the bridge and against threads that may be drawn between the rib and bridge and through the pot and its base openings.

4. In combination, a wax pot having a 75 plurality of base openings and a laterally directed flange at its upper edge, said flange having notches in its opposite side adjacent the edge of the pot, a bridge member, comprising a wire having down-turned end portion, mounted transversely across said flange with said down-turned ends extended into said flange notches, a tensioning plate mounted on the flange having a transverse rib seated upon the bridge to engage threads 85 drawn across the latter and through the pot openings, and having openings through which said threads may be extended to be drawn across the bridge and a screw extended through said plate and pot flange, 90 having a nut adjustable thereon to regulate the tension of the plate against the threads.

Signed at Tacoma, Washington, this 19th day of February, 1920.

CARL A. ALEXANDER.
ERIC W. YOUNG.
